UNITED STATES PATENT OFFICE.

WILLIAM H. TALLETT, OF WATERTOWN, NEW YORK.

FISHING-ROD.

1,098,769.

Specification of Letters Patent.

Patented June 2, 1914.

Application filed June 14, 1913. Serial No. 773,694.

To all whom it may concern:

Be it known that I, WILLIAM H. TALLETT, a citizen of the United States, residing at 1030 Coffeen street, Watertown, in the 5 county of Jefferson and State of New York, have invented certain new and useful Improvements in Fishing-Rods; and I hereby declare the following to be a full, clear, and exact description of the invention, such as 10 will enable others skilled in the art to which it appertains to make and use the same.

This invention relates to a fishing rod, and particularly to a sectional steel rod.

An object of the invention is the provision 15 of a sectional steel rod having a reinforcing winding of suitable thread covering the entire rod and coated with a suitable water proofed composition to prevent the steel from becoming rusted.

Another object is to provide multiple 20 windings of suitable thread at the weak points in the joints between the sections, to strengthen these points without detracting from the desirable flexibility of the rod.

A further object is to provide a steel fishing rod with a copper coating or plating and an outer covering of suitable water proofed thread for rendering the rod impervious to salt air, and water.

In the accompanying drawing, Figure 1, represents a side elevation of a complete rod of ordinary construction entirely covered with my improved winding. Fig. 2, represents a fragmentary view in side elevation 35 of the joint between two sections of the rod, partly broken away, and showing the windings in section. Fig. 3, represents a fragmentary view of a section of a rod, showing a portion thereof wrapped and a portion 40 exposed. Fig. 4, represents a transverse sectional view through Fig. 3, and Fig. 5, represents a fragmentary view partly in section of a portion of the rod showing one of the line receiving eyes.

Referring to the drawing, wherein similar reference numerals designate corresponding parts throughout the several views, the 45 numeral 10 indicates a complete sectional steel rod of ordinary construction having my improved reinforcing winding to be hereinafter described.

The ordinary rods manufactured of metal are formed in sections and of sheet material

of tubular formation, having a longitudinal seam 11. The objection to the seam is that 55 it permits water to gain access to the interior of the rod and to the edges of the section, and to rust these parts. The ferrules 12 are brazed to the large ends of the sections, and during this process that end of 60 the section is obviously heated, sometimes to such a degree as to materially harden that portion of the section, and render the rod likely to breakage at this point.

In carrying out my invention, I wind each 65 section of the rod 10 with a thread 13 of a suitable gage and material. The first winding or covering 13, is wrapped in very close coils about the sections of the rod and so as to positively prevent the water gaining 70 access to the interior of the sections through the seams 11 therein. However, to further guard against the admission of water, I coat the winding or covering 13 with a suitable water proofing composition, such as shellac. 75 The large ends of the sections of the rod to which are brazed the ferrules 12, are further reinforced by two extra windings of thread 14 and 15, as clearly shown in Fig. 2. The intermediate winding 14 extends 80 from the end of the ferrule 12, a distance inwardly on the section of the rod 10, and surrounds the first covering 13, while the outer covering 15, extends from the ferrule 12, a shorter distance inwardly on the sec- 85 tion.

It is obvious that the extra windings 14 and 15 will materially strengthen the rod at the point which is most likely to be the weakest. To insure against these reinforcing windings or coverings from becoming water soaked and consequently widened, a suitable water proofed composition may be also coated thereover.

In order that the steel rod may effectively 95 withstand the deteriorating influence of salt air and water the rod may be coated or plated, electrically or otherwise with a layer of copper of adequate thickness. It will be understood the copper is to be applied di- 100 rectly to the steel of the rod, and thereafter covered with the windings therein described.

What I claim is:

In combination, a sectional steel fishing rod having a ferrule brazed to one end of 105 each section and adapted to receive the end

of the next section, separate windings of
thread covering each section from the end
to the ferrule, and additional windings form-
ing multiple layers extending from the fer-
rule of each section various distances in-
wardly.

In testimony whereof I have signed my

name to this specification in the presence of
two subscribing witnesses.

WILLIAM H. TALLETT.
